US00D630436S

(12) **United States Design Patent**
Winkler

(10) **Patent No.:** **US D630,436 S**
(45) **Date of Patent:** ** *Jan. 11, 2011

(54) **TOOTHBRUSH**

(75) Inventor: **Tilmann Winkler**, Kronberg (DE)

(73) Assignee: **Braun GmbH**, Kronberg (DE)

(**) Term: **14 Years**

(21) Appl. No.: **29/335,993**

(22) Filed: **Apr. 27, 2009**

(30) **Foreign Application Priority Data**

Oct. 27, 2008 (EM) 001028401

(51) **LOC (9) Cl.** **04-02**

(52) **U.S. Cl.** **D4/104**

(58) **Field of Classification Search** D4/101,
D4/104–112, 134, 138; 15/143.1, 167.1,
15/167.2; 132/308–311; 604/139, 141

See application file for complete search history.

(57) **CLAIM**

The ornamental design for a toothbrush, as shown and described.

DESCRIPTION

FIG. 1 is a perspective view of a first embodiment of a toothbrush, showing my new ornamental design;

FIG. 2 is a back view thereof;

FIG. 3 is a bottom view thereof;

FIG. 4 is a front view thereof;

FIG. 5 is a right-side view thereof;

FIG. 6 is a left-side view thereof; and

FIG. 7 is a top view thereof.

FIG. 8 is a perspective view of a second embodiment of a toothbrush, showing my new ornamental design;

FIG. 9 is a back view thereof;

FIG. 10 is a bottom view thereof;

FIG. 11 is a front view thereof;

FIG. 12 is a right-side view thereof;

FIG. 13 is a left-side view thereof; and,

FIG. 14 is a top view thereof.
